FOOTBALL GAME

Frank A. Caso, New York, N. Y.

Application September 13, 1939, Serial No. 294,614

1 Claim. (Cl. 116—120)

This invention relates to new and useful improvements in a football game apparatus.

More specifically the invention proposes the construction of a football game apparatus characterized by a board, complete in itself for permitting a modified game of football to be played, and which may be folded up in a manner to be conveniently carried about in one's pocket.

Still further it is proposed to characterize the board by an elongated slot with a football field representation along the sides of the slot, and in back of which a slide member is movably mounted and having a football element thereon, and adapted to be shifted to various positions along the length of the slot in a manner to indicate the progress of the game.

Still further it is proposed to provide the board with a chance control means for directing movement of the football element up and down the field representation in accordance with standard football plays.

Still further it is proposed to provide a marker adapted to be shifted along the length of the field representation and which is drawn to the same scale as the field representation in a manner to permit the "downs" to be calculated for determining whether or not the person playing the game has made a first "down" or not.

Still further it is proposed to provide a means for holding the marker in various adjusted positions along the length of the field representation in a manner to permit the same to be shifted to an aligned position with the football element of the slide member.

A further object of the invention is the provision of a list of the current football games in any particular season upon the back of the slide member in a manner to be viewed through an elongated slot formed in the back of the member which movably supports the slide member.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the football game apparatus in its folded condition.

Fig. 2 is a plan view of the football game apparatus in an unfolded condition without the down mark in position thereon.

Fig. 3 is a sectional view on the line 3—3 of Fig. 2.

Fig. 4 is a sectional view on the line 4—4 of Fig. 2.

Fig. 5 is a sectional view on the line 5—5 of Fig. 2.

Fig. 6 is a rear view of the panel of the apparatus enclosing the slide.

Fig. 7 is a rear elevational view of the slide, per se.

Fig. 8 is a front perspective view of the marker used for determining the downs.

Fig. 9 is a fragmentary view similar to a portion of Fig. 2 illustrating the down mark in position on the field representation.

Fig. 10 is a sectional view on the line 10—10 of Fig. 9.

Fig. 11 is a perspective rear view of the marker per se.

The football game apparatus according to this invention includes a board 10 formed of card board or other similar material and divided into a plurality of panels 10^a, 10^b, and a tubular panel 10^c foldably connected together in a manner to be folded to assume the position shown in Fig. 1 in which it is possible to conveniently carry the apparatus in one's pocket. The tubular panel 10^c has a portion 10^d of the board 10 folded upon itself forming the tubular portion. The portion 10^d is formed with an elongated slot 11 having a football field representation 12 along the sides thereof.

This football field representation comprises a rectangular area having a plurality of lines extended thereacross and the margin of the football field representation is imprinted with a plurality of numbers successively readable in opposite direction and increased by five's. This is to indicate that each of the lines is five yards apart and that the field is one hundred yards long in a manner similar to all football fields. A slide member 13 is slidably engaged into tubular panel 10^c and is movably mounted along the length of the slot 11 and has football field representation 14 imprinted thereon and drawn to the same scale as the football field representation 12 of the portion 10^d.

A football element 15 is imprinted upon the center of the football field representation 14 of the slide 13 and has an arrow 15^a which is adapted to be aligned with the yard lines of the football representation 12 in a manner to indicate the positions of the football on the field representation during the process of playing the game. The ends of the tubular member are cut away as shown at 16 on both sides of the slide 13 in a manner to permit the ends of the slide to be

50 55

grasped for moving the same along the length of the slot 11.

The board 10 is further provided with a chance controlled means for directing motion of the foot-ball element 15 up and down the football field representation 12 in accordance with standard football plays. This means is mounted on the panel 10^b of the board 10 and comprises a rotatively mounted spinner 17. This spinner is coaxially rotatively supported over a dial 18 imprinted upon the face of the panel 10^b. This dial 18 is subdivided into a plurality of smaller areas 18^a each of which carries a number. For the purpose of illustration the dial has been subdivided into twelve areas and these areas have been successively numbered from one to twelve. The spinner 17 is rotatively supported by a means of an eyelet 19 which is rotatively passed through the spinner and through the panel 10^b of the board 10 and coaxial with the dial 18.

This chance control means further includes a rectangular area 20 imprinted upon the right hand side of the panel 10^b. This area 20 is subdivided into a plurality of boxes. The vertically arranged boxes 20^a along the left hand side of the area 20 are successively numbered from one to twelve to correspond with the numbers of the dial 18. The horizontal top row of boxes 20^b are imprinted with a plurality of possible plays for the average football game. The remaining boxes 20^c are imprinted with the results of a particular play. The top row 20^b might be imprinted successively with the following legions: kick-off, return, left or right end run, left or right tackle, left or right guard, off center, punt, return punt, forward pass, trick play, drop kick, and placement.

In playing the game it is necessary that the player spinning the spinner 17 determine the type of play he wishes to try before he spins the spinner and when the spinner stops he notices the number and carries the number across in the area 20, to the vertical row of the play he tried to determine the result thereof and correspondingly moves the slide to indicate the results. The panel 10^b above the dial 18 is imprinted with an area 21 which gives the scores resulting from the touchdown, the point after touchdown, place kick, drop kick, and a safety. These scoring valves are the same as in a conventional football game.

The panel 10^b below the dial 18 has an area 22 imprinted with the rules of the game. These rules are as follows: 1. A player may not attempt a drop kick or placement unless he is within the twenty yard line. 2. When a ball is pushed in back of the goal by losses on downs, it is called a safety which counts two points for the opposing side. 3. After each kick or punt ball is lost to opposing team. 4. A five yard penalty is given for failing to call play before spinning. The panel 10^b further has an area 23 below the area 20 which is imprinted with a plurality of squares numbered from one to four permitting the score of each quarter of the game to be marked therein.

The back faces of the slide 13 is imprinted with a football schedule of important football games in any one particular season which is adapted to be viewed through an elongated slot 24 formed along the width of the panel 10^c on the back thereof. Above this slot the panel is imprinted with the words, date, college, opponent, place, and the last year's record. When the particular line of the schedule is brought into alignment

with the slot 24 it will be possible to determine the date of the particular game, the college, the opponent, and the location of the field upon which the game is to be played as well as the results of the previous year's game if the two colleges played in that year. The rear view of the slide is shown in Fig. 7. The panel 10^a is imprinted with instructions on how to play the football game with this apparatus and which read as follows: The game is played by two people. More than one can play on each side, and each player takes turns spinning until the ball is lost. Each side chooses a goal. The opening kickoff is decided by choice. Length of the game is thirty minutes—fifteen minutes for each half or as long as desired.

The team kicking off, spins. The spinner number determines the yardage of the kick. Refer to column "kick-off" to see number of yards. Suppose you spin No. 6. You will find that you gained 55 yards. Place the slide so that the ball is on the 40 yard line (as game starts at this point), and advance 55 yards which brings it to the 95 yard line. After the kickoff the other side spins. The spinner determines the yardage of the return kickoff. See columns "return." Suppose the number is 5. Then the team returns the ball 10 yards, that is from its own five yard line to its own 15 yard line. After the return has been made the same team calls its play: end, tackle, forward, pass, etc., and spins. Suppose he calls "off center" and the spinner stops at 8. He refers to column marked Off center and finds that spinner number 8 is a five yard advance. He then advances the ball on the slide from the 15 yard line to the 20 yard line. It is now second down (or play) and five yards to go. He calls another play, say "trick play" and then spins. If it stops at 3 he will find in column marked Trick play 25 yard line. (The team has made ten yards and therefore has made first down.) Either team gaining 10 yards or more within 4 plays is entitled to first down and retains the ball for another 4 plays and as often as he makes his 10 yards within 4 plays. When a team does not gain the necessary 10 yards in 4 plays, the opposing team gets the ball and proceeds in the same manner in the other direction at the point where the play ended. The ball is always kicked off at the beginning of first half, the second half and after each touchdown.

The apparatus further includes a marker 25 shown in Fig. 8 for measuring the downs and it is drawn to the same scale as a football representation for determining whether or not the side has made a first down within a prescribed number of chances in a manner similar to a standard football game. This marker is drawn to the same scale as the football field representation 12 and to follow the progress of the ball during four downs, the arrow marked first down, second down, third down, fourth down are successively moved to the position of the ball at the start of the first down. If the ball passes beyond the point of any arrow the required 10 yards has been gained and the opposing side has succeeded in making the necessary yardage for registering the first down and the marker is again aligned with the football element 15 imprinted upon the slide 13.

A means is provided for holding the down mark 25 in position along the length of the slot 11 formed in the portion 10^d. This means comprises a pair of spring clips 26 mounted on each end of the down mark 25. These clips 26 are

adapted to engage over the bottom edge of the slot 11 as shown in Figs. 9 and 10. When the mark is extended in the direction indicated by the dot and dash line 25^a the spring clips 26 at one end of the marker are adapted to engage over the slot 11 while the spring clips 26 at the other end of the marker remain inoperative. In the same manner, when the marker is extended in the direction of the dot and dash lines 25^b the spring clips 26 at the other end of the marker are adapted to engage over the slot 11 while the spring clips at the aforementioned end of the marker remain inoperative.

The rear face of the panel 10^a may be imprinted with a suitable title for the game as shown in Fig. 1 and blank spaces thereof may be suitably imprinted with advertising material. In the same manner the rear faces of the panel 10^b and the rear faces of the panel 10^c below the slot 24 may be imprinted with desired advertising material.

The operation of this form of the device is as follows:

The players desiring to play the game split up into two teams and decide which side is to kick off and which receive. Thereupon the player who decides to kick off, spins the spinner 17 and notices the number. He then looks into the area 20 along the vertical area 20^a to get the corresponding number and then carries the number across to the kick-off column to determine how far the kick went and moves the ball. The ball is then in the hands of the opposing team and the players from the opposing team determine the type of play he wishes to try and then spins the spinner 17. He carries the number at which the spinner stops across the area 20 to the column of the play he wished to try and determines the results thereof. He then moves the slide to cause the football element to be properly aligned with the yard line of the field representation 12 to indicate the results of the play.

In the same manner each player of the team spins the spinner 17 in an attempt to make the

necessary 10 yards, within four downs for receiving another first down. If they fail to make the necessary yardage the ball then goes to the opposing team and they then attempt to move the ball into the opposite direction towards the goal and so the game continues, until one side makes a goal or the end of the period is reached after which the ball is again kicked-off in a manner similar to the conventional football game.

10 It is to be understood that the game may be arranged for use as baseball, basketball and like games, also for recording the progress and score of games broadcast over the radio.

15 While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

20 In a football game apparatus, a flat tubular board having an elongated slot formed in one side thereof, a football field representation imprinted along the sides of said slot, a slide slidably engaged into said tubular member, a football element imprinted on said slide in an aligned position with said slot so as to be movable to various positions relative to said football field representation to indicate the position of a football on a field, and a marker drawn to the same scale as said football field representation and shiftable 25 along the length of said slot in a specific relationship to the movement of said football element to record the down and the number of yards that must be gained to get another first down, and means for holding said marker in adjusted fixed positions along the length of said slot, comprising spring clips mounted upon the back face of said marker and engageable over the edge of said slot and slidable therealong.

30 FRANK A. CASO.
